[57] CLAIM

The ornamental design for a fireplace grate, substantially as shown and described.

DESCRIPTION

FIG. 1 is a perspective view of a fireplace grate, showing my new design;

FIG. 2 is a side elevational view thereof;

FIG. 3 is an end elevational view thereof;

FIG. 4 is an elevational view of the opposite end;

FIG. 5 is a top plan view thereof;

FIG. 6 is an elevational view of the side opposite that shown in FIG. 2;

FIG. 7 is a bottom plan view thereof;

FIG. 8 is a perspective view of a second embodiment of a fireplace grate;

FIG. 9 is a side elevational view thereof;

FIG. 10 is an end elevational view thereof;

FIG. 11 is a bottom plan view thereof.

Fig. 1.Fig. 3.Fig. 2.Fig. 4.Fig. 5.Fig. 6.Fig. 7.
